UNITED STATES PATENT OFFICE.

JAMES RUSSELL WARREN AND GEORGE WESTERN PACKARD, JR., OF DEADWOOD, SOUTH DAKOTA.

ADVERTISING DEVICE.

No. 919,096.

Specification of Letters Patent. Patented April 20, 1909.

Application filed June 12, 1907. Serial No. 378,491.

To all whom it may concern:

Be it known that we, JAMES RUSSELL WARREN and GEORGE WESTERN PACKARD, Jr., citizens of the United States, and residents of Deadwood, in the county of Lawrence and State of South Dakota, have invented a new and Improved Advertising Device, of which the following is a full, clear, and exact description.

10. The invention relates to advertising devices or signs using the tumbling panels known as "Jacob's ladder", and its object is to provide a new and improved advertising device arranged to allow viewing the 15 signs from both sides and to display four different legends on each sign, thus increasing the capacity of the advertising device without increasing the bulk thereof.

The invention consists of novel features 20 and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a perspective view of the improvement; Fig. 2 is a transverse front section of the same on the line 2—2 of Fig. 3; Fig. 3 is a sectional front elevation of the same on the line 3—3 of Fig. 2; Fig. 4 is an enlarged rear view of the two uppermost signs; Fig. 5 is a like view of the same in a 35 reverse position; Fig. 6 is an enlarged cross section of the uppermost sign, the section being on the line 6—6 of Fig. 4; Fig. 7 is a sectional view of one of the signs, the section being on the line 7—7 of Fig. 1. Fig. 40 8 is a perspective view of one of the signs.

In a suitably constructed casing or frame A is journaled a rock shaft B, to which is attached the uppermost sign block C' of a Jacob's ladder C having a suitable number 45 of sign blocks C², C³, C⁴, C⁵ supported one below the other by suitable bands C⁶, so that when the shaft B is alternately rocked the distance of half a revolution forward and backward, then the blocks are tumbled in 50 the usual manner, as is well known in the construction of Jacob's ladders as heretofore used. Each of the blocks C', C², C³, C⁴, C⁵ is provided with letters or other suitable indicating characters D and the front and 55 rear faces of the bands C⁶ are provided with

letters E and E' adapted to be complementary with the letters D on the corresponding blocks, so as to produce a complete legend on each face of each sign. For the purpose mentioned, the two bands C⁶ for each block 60 are together approximately of a width corresponding to one-half the width of a block C', C², C³, C⁴, C⁵, and the said bands are alternately near the edges of the blocks and then at the middle thereof, as will be readily 65 understood by reference to Figs. 1, 3, 4 and 5. Now as each band has letters at both the front and rear faces thereof, and each band covers up a letter or character on the corresponding block, some of the letters 70 on the block as well as the letters on the back face of the bands on this block are hidden from view, still a complete legend appears visible to the eye. Thus by reference to Fig. 1 it will be seen that the second 75 block from the top shows the legend "Corn" at the front, and the legend "Lard" at the back (see Fig. 4), and when a half revolution is given to the shaft B and consequently to the first block C', 80 then the blocks are reversed and the second block discloses at its front face the legend "Pork", as shown in Fig. 3, and the legend "The best" at the back, as illustrated in Fig. 5. Thus each block forms a 85 complete sign in itself having four different legends, of which two are displayed alternately at the front face of the advertising device and two at the rear face thereof.

In order to impart the desired rocking motion to the shaft B the following construction is provided: On the shaft B within the casing or frame A is secured a pinion F engaged by a rack F' pivotally connected with a crank G journaled in the casing or frame A and carrying a pinion H connected by a train of gear wheels H' with a spring barrel I of any approved construction, so that a continuous rotary motion is given to the pinion H and crank G, to cause the rack 95 F' to alternately turn the pinion F and consequently the shaft B forward and backward, for tumbling the blocks of the Jacob's ladder C, as above explained. Other suitable mechanism may be employed for alternating the half-turn rocking motions in opposite directions to the shaft B, as above explained.

The blocks are connected together in the following manner. The first block, Fig. 8, 110

is connected by four bands with the second block, two of said bands being secured to the front face of the first block near the upper end thereof, passing over said upper 5 end and around the back of said first block to the front face of the second block being secured near the upper end thereof. The other two bands are secured to the same face of the first block but at the lower end and 10 near the edges of the block, and passing directly behind the second block are secured in corresponding positions on the front face of the second block. The second block is connected with the third block by means of 15 two bands, the bands being secured to the lower edge of the rear face of the second block at the center thereof, and extending down the front of the third block to the back of the said third block and being secured in 20 a position corresponding to their point of attachment to the second block. The third block is secured to the fourth block in the same manner as the first block is secured to the second block, and the fourth block is secured to the fifth block in the same manner 25 as the second block is secured to the third block.

Having thus described our invention, we claim as new and desire to secure by Letters 30 Patent:

1. An advertising device provided with a "Jacob's ladder" having tumbling blocks provided on each face with indicating characters, and bands supporting the blocks one 35 above the other, the bands having indicating characters on both faces.

2. An advertising device provided with a "Jacob's ladder", having tumbling blocks provided on each face with indicating characters, and bands supporting the blocks one 40 above the other, the bands having indicating characters on both faces and the bands being arranged to cover up indicating characters on the blocks when the bands are in certain positions.

3. An advertising device provided with a "Jacob's ladder", having tumbling blocks provided on each face with indicating characters, and bands supporting the blocks one 45 above the other, the bands having indicating characters on both faces, the indicating characters on the said blocks and the indicating characters on the said bands being complementary.

4. An advertising device comprising a 55 power - driven rocking mechanism, and a "Jacob's ladder" having tumbling blocks and bands for supporting the blocks one above the other, the uppermost block being attached to a rock shaft of the said rocking 60 mechanism, and the said blocks and bands being provided on each face with indicating characters, the characters on the said blocks and bands being complementary.

In testimony whereof we have signed our 65 names to this specification in the presence of two subscribing witnesses.

JAMES RUSSELL WARREN.
